(57) **CLAIM**

The ornamental design for a robot cleaner with base station, as shown and described.

DESCRIPTION

FIG. 1 is a perspective view of a robot cleaner with base station in a state of use in accordance with the present design;

FIG. 2 is a perspective view of the robot cleaner in accordance with the present design, shown separately for clarity of illustration;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a perspective view of the base station in accordance with the present design, shown separately for clarity of illustration;

FIG. 9 is a front view thereof;

FIG. 10 is a rear view thereof;

FIG. 11 is a left side view thereof;

FIG. 12 is a right side view thereof; and,

FIG. 13 is a top view thereof.

1 Claim, 13 Drawing Sheets
